UNITED STATES PATENT OFFICE.

EVAN B. JONES, OF LA GRANDE, OREGON.

GLOVE.

1,231,168.

Specification of Letters Patent. Patented June 26, 1917.

Application filed September 19, 1916. Serial No. 121,005.

To all whom it may concern:

Be it known that I, EVAN B. JONES, a citizen of the United States, residing at La Grande, in the county of Union, State of Oregon, have invented certain new and useful Improvements in Gloves; and I do hereby declare the following to be a full, clear, and exact description of the invention, such as will enable others skilled in the art 10 to which it appertains to make and use the same.

This invention relates to gloves and has special reference to a combined glove and cleaning flap attached thereto, the complete 15 article being for the purpose of washing dishes, dusting, polishing or the like.

One important object of the invention is to provide an improved and simple device of this character.

20 A second important object of the invention is to provide a device of this character wherein the flap is so attached to the glove that it may be opened up for the purpose of cleansing the glove and flap.

25 With the above and other objects in view, as will be hereinafter apparent the invention consists in general of certain novel details of construction and combinations of parts hereinafter fully described, illustrated in 30 the accompanying drawings, and specifically claimed.

In the accompanying drawings, like characters of reference indicate like parts in the several views, and:—

35 Figure 1 is a front view of the glove and flap, the flap being shown as folded back in full lines and in its attached position in dotted lines.

Fig. 2 is a back view thereof.

40 Fig. 3 is a detail showing the glove before the flap is applied thereto.

Fig. 4 is a detail view of the flap detached from the glove.

Fig. 5 is a front view similar to Fig. 1 45 but showing a modified form of the device.

Fig. 6 is a view similar to Fig. 4 and showing a modified form of quilting used in connection with the device.

Fig. 7 is a transverse section through the 50 flap showing the reinforcing therefor.

In the embodiment of the invention herein illustrated there is shown a glove which is provided with a palm portion 10, a thumb stall 11 and a stall for the forefinger as at 55 12. The remaining three fingers are held in a common stall 13.

At 14 is a flap which is preferably made of some quilted material and of double thickness. This flap is attached to the back side of the forefinger stall 12 by means of a row 60 of stitching 15, the stitching being continued around the base of the thumb as at 16. Moreover, the flap is secured as at 17 to the base of the outer metatarsal portion of the palm of the glove and on the back to the 65 inner metatarsal portion as indicated at 18. Mounted on the portion 13 of the glove is a snap button member 19 which co-operates with a similar snap button member 20 mounted on the flap 14. It will be observed 70 that this flap 14 projects all around the extremities of the glove and the outer side thereof as clearly seen in Fig. 2.

By means of this construction the movements of the forefinger and thumb of the 75 user in washing dishes are not restricted so that the possibility of a dish slipping from the hand is practically eliminated. Furthermore, the arrangement which holds the flap extending across the glove prevents the 80 flap from doubling up into a ball in the palm of the hand while at the same time, when it is desired to wash the glove and flap, access is afforded to the inner side of the flap and the palm portion of the glove by simply releasing the snap button parts 19 and 20 85 from each other.

In the form shown in Fig. 5 the fastening at 17 is preferably made detachable, the ordinary button 21 and snap socket 22 being employed at this point as clearly shown in this figure. This form has the advantage of affording complete access to the inside of the flap 14 so that it may be more readily washed than where the flap is permanently 95 secured as indicated in Figs. 1 to 3.

The rectangular quilting shown in Figs. 1 to 5 may be modified also as shown in Fig. 6 wherein a spiral quilting 23 is employed.

For certain purposes it is also advisable 100 to make the flap in two thicknesses as indicated at 24 in Fig. 7, the flap being reinforced by a stiff filling 25 quilted to the thicknesses as at 27 the thicknesses 24 being connected by stitching 26 at their edges. 105

Furthermore when the device is to be used dry, as for instance in dusting or polishing, it is preferred that the cuff be made of knitted material as disclosed at 27 in Figs. 1, 2 and 3. When, however, the device is to 110 be used for washing or other wet work it is preferred that the cuff be made of rubber.

as indicated at 28 in Fig. 5. It will be obvious that in place of the rubber any suitable elastic material may be used.

There has thus been provided a simple and efficient device of the kind described and for the purpose specified.

It is obvious that many minor changes may be made in the form and construction of the invention without departing from the material principles thereof. It is not therefore desired to confine the invention to the exact form herein shown and described but it is wished to include all such forms as properly come within the scope claimed.

Having thus described the invention, what is claimed as new, is:—

The combination with a glove and a flap therefor covering the entire glove, of means to secure said flap to said glove and prevent

wrinkling up of the flap and consisting of a line of stitching connecting one side of the flap to the glove from a point at the wrist on one side of the base of the glove thumb around the thumb between said thumb and the finger portion of the glove to a point at the wrist on the other side of the base of the thumb, a snap button detachably connecting the flap with the glove adjacent the extremity of the little finger of the wearer, and a second snap button detachably connecting the flap with the glove at the portion adjacent the wrist and opposite the thumb.

In testimony whereof, I affix my signature, in the presence of two witnesses.

EVAN B. JONES.
